EXTENDED GUSSET FOR LADIES' HAND BAGS.

Application filed July 9, 1925. Serial No. 42,429.

This invention relates to improvements in ladies' pocket-books or the like, more particularly to an extended gusset for ladies' pocket-books, handbags, vanity cases, etc., and it is the principal object of the invention to provide a ladies' pocket-book or handbag or the like with an extended gusset which will positively and efficiently prevent the accidental dropping out of articles contained therein either in the closed or in the open position of the hand-bag, etc.

Another object of the invention is the provision of a simple, novel and improved means to provide ladies' hand-bags etc. with a gusset adapted to be folded within the handbag to effectively prevent loss of articles and to allow a ready access to the interior of the hand-bag.

A further object of the invention is the provision of an extended gusset for ladies' pocket-books, hand-bags or the like attached to the side faces thereof adapted to fold against the front or rear wall of the container.

A still further object of the invention is the provision of an extended gusset for ladies' hand-bags or the like adapted to be held in close relation to the front and rear walls thereof and to be folded along predetermined lines.

It is furthermore an object of the invention to provide an extended gusset for ladies' pocket-books, hand-bags or the like having its upper flaps connected and allowing the attachment of a purse etc. at its sides.

These and other objects and advantages of the invention will become more fully known as the description thereof proceeds, and will then be specifically pointed out or defined in the appended claims.

In the accompanying drawing, forming a material part of this disclosure:

Figure 1 is a perspective view of a lady's pocket-book or hand-bag equipped with extended gussets constructed according to the present invention.

Figure 2 is a front elevation of the lady's hand-bag constructed according to a modified form of my invention.

Fig. 3 is an end view of another modification of the invention, particularly of the stitching of the gusset.

Fig. 5 is a fragmentary detail view of a gusset having a purse attached thereto.

The lady's hand-bag or pocket-book, 10 has the customary extended rear wall 11 formed in the usual manner to fold over the shorter front wall 12 and to be locked by means of the customary snap button 13 on the wall 11 adapted to engage a socket 14 on the front wall 12. Gussets 15 and 16 are attached by a seam 17 to the inner face of the rear wall 11, and allow a lateral unfolding of the gusset from said rear wall.

The opposite edge of the gussets, the inner one, is attached for part of its length by a seam 18 to the inner wall of the front wall 12 over the entire width thereof allowing a folding of the gussets along a fold 19 during the closing of the hand-bag.

The oppositely disposed inner edges of the gussets are disposed parallel to each other as at 20 and 21, while their upper ends are curved as at 22 and 23 respectively to their point of attachment with the rear wall 11, leaving along said rear wall a flange 24 along which the gussets are unfolded upon the opening of the bag.

In the modified form illustrated in Figure 2, the gussets 25, 26 are similarly constructed as described with respect to the preferred form, with exception of their formation with outer side flaps 27, 28 adapted to be secured to the rear wall 11 by means of snap buttons 29, and similar snap buttons 30 secure the folded lower end of the gussets to the hand-bag.

A strap 31 secured at one end to gusset 26 intermediate its ends is adapted to be attached to the opposite gusset 25 by means of a snap button 32 or the like. The pocket formed by the front wall and the rear wall may be adapted to receive and hold a pocket-book 33 attached therein in any suitable manner, and any number of pockets may be formed between the lining or stiffenings in the hand-bag and the outer and inner walls thereof, as indicated at 34, 35.

In the modifications of the gussets illustrated in Figures 3, 4 and 5, in end views, the gussets 36, 37 and 38 respectively are formed with or attached to the rear walls 39, 40, 41 of the hand-bag in the above described manner, only they are provided with varying kinds of seams allowing a folding of the gussets along the same. The gusset 36 has a central horizontally disposed seam 42, and an obliquely disposed fold 43, while the gusset 37 has an angular, obliquely disposed seam 44 formed therewith allowing a folding of the gusset between front and rear wall of the hand-bag.

A purse 45 having a closing flap 46 adapted to be closed by a snap button 47 may be attached to the gusset 38 in any well known manner.

It will be understood that the gussets formed and attached as shown and described will allow a convenient opening of the pocket book or hand-bag without danger of loosing articles contained therein which is frequently experienced by persons using the hand-bags now on the market.

While we have shown and described the preferred forms of our invention as an example of the practical embodiment thereof, it will be understood, that such changes as fall within the scope of the appended claims may be made in the construction and arrangement of the device without departure from the spirit of the invention.

Having thus described our invention, what we claim as new and desire to secure by Letters Patent is:

1. The combination, in a lady's pocket-book of the class described, of a pair of extended gussets, means for detachably fastening said gussets to a pocket-book, and a strap fixed at one end to one of said gussets, and provided with means at its other end to detachably hold the other of said gussets, whereby the strap may hold said pair of gussets as a unit, if desired to be removed from the pocket-book and stored for a period of time. 40

2. A unitary pair of extended detachable gussets for ladies' hand-bags, comprising a pair of extension gussets, snap fasteners mounted along the gusset edges for detachably fastening to a hand bag, and a strap 45 sewed at one end to one of said gussets, and provided with a snap fastener at its other end to detachably hold the other of said gussets.

In testimony whereof we have affixed our 50 signatures.
